UNITED STATES PATENT OFFICE.

JACOB TEPFER, OF BROOKLYN, NEW YORK.

SLIP-RING.

1,250,109.

Specification of Letters Patent. Patented Dec. 11, 1917.

Application filed February 15, 1917. Serial No. 148,922.

To all whom it may concern:

Be it known that I, JACOB TEPFER, a citizen of the United States, and a resident of the city of New York, borough of Brooklyn, 5 in the county of Kings and State of New York, have invented a new and Improved Slip-Ring, of which the following is a full, clear, and exact description.

My invention relates to a slip ring, and 10 an object is to provide a simple and inexpensive ring formed of a single blank.

Another object is to provide a slip ring of comparatively little weight and great strength.

15 Reference is to be had to the accompanying drawings, forming part of this specification, in which like characters indicate corresponding parts in both views.

Figure 1 is a section through a light fixture provided with a slip ring embodying my invention; and

Fig. 2 is a perspective view of my ring partly in section to show the construction.

Referring to the drawings, the ring 3 consists of an inner tubular part 4 and an outer collar 5 semicircular in cross section and pre-

senting an outer convex surface, one edge of which collar is integral with an edge of the tubular member 4. The portion 5 is punched inwardly toward the tubular portion 4 to 30 form a socket 6 with which an aperture 7 in the tubular portion is in register, both being threaded to receive a set screw 8 by means of which the ring can be locked.

The ring is formed from a blank the central part of which is punched to form the tubular portion 4, the margin of the blank being used to form the collar 5. To form the ring, two operations only of the punch are required. The resulting ring is very 40 light and rigid and it is a unit in itself.

I claim:

As an article of manufacture, a slip ring shaped from a blank to present a tubular portion terminating at one end with an outer 45 collar of semicircular cross section, the end of the collar resting against the tubular portion, said collar presenting an inwardly-directed socket for which the tubular member presents an alining aperture, both being 50 adapted to receive a set screw.

JACOB TEPFER.
